Inventor:
Albert Hundt,
by *Albert Hundt, D.A.*
His Attorney.

UNITED STATES PATENT OFFICE.

ALBERT HUNDT, OF PANKOW, GERMANY, ASSIGNOR TO GENERAL ELECTRIC COMPANY,
A CORPORATION OF NEW YORK.

ELECTRICAL APPARATUS.

1,160,716.

Specification of Letters Patent. Patented Nov. 16, 1915.

Application filed May 25, 1915. Serial No. 30,301.

To all whom it may concern:

Be it known that I, ALBERT HUNDT, a subject of the King of Prussia, residing at Pankow, Germany, have invented certain new and useful Improvements in Electrical Apparatus, of which the following is a specification.

My invention relates to windings for electrical apparatus, particularly to high voltage windings for transformers.

The object of my invention is to provide for the protection of such windings against the more or less transient disturbances to which they are likely to be subjected and which generally originate outside the windings.

To this end I parallel the end coils or portions of each winding, or the coils or portions of the winding likely to be subjected to the disturbances, with a special or auxiliary coil in such a manner that the two coils (or the auxiliary winding and the portion of the main winding paralleled thereby) form a condenser, the auxiliary coil or winding being connected to ground. The coils or portions of the main winding, with which the auxiliary coil or winding is associated, are substantially those which are extra heavily insulated according to prior practice. The connection to ground may be made through any one of various safety devices, some of which will be later described more in detail.

In the following description and the accompanying drawing, I have described and illustrated certain embodiments of my invention.

Figure 1 diagrammatically illustrates a simple embodiment of my invention; and Figs. 2 and 3 illustrate diagrammatically two safety devices in the grounding connection.

In Fig. 1, the electrical winding, with which my invention is shown associated, is composed of the coils 1, 2, 2, etc., the terminal being attached at 3. The special or auxiliary coil or winding 4 is in parallel with the turns of the end coil 1 in such a manner

that the two coils form a condenser. The auxiliary winding 4 is connected to ground 5 by the connection 6. In this case the connection 6 is attached to the center of the coil 4, but the grounding of the winding 4 may of course be effected at one of the two ends or at any desired place in the center of the coil. In this case also the connection 6 is uninterrupted. It may, however, be provided with safety devices of various sorts for limiting the flow of energy over it. Two examples of this are shown in Figs. 2 and 3 wherein respectively a spark gap is illustrated at 7 and an ohmic resistance at 8. This arrangement may be used in various places and with various constructions, but is of special importance with railway transformers where often there is hardly sufficient space for a special condenser. The arrangement also allows the insulation of the end coils from turn to turn to be conveniently tested.

While I have described the principle of my invention and the best mode I have contemplated for applying this principle, other modifications will occur to those skilled in this art and I aim in the appended claims to cover all modifications which do not involve a departure from the spirit and scope of my invention.

What I claim as new and desire to secure by Letters Patent of the United States, is,—

1. The combination with an electrical winding, of a grounded auxiliary winding arranged in parallel with the end turns of said electrical winding and forming a condenser therewith.

2. The combination with an electrical winding, of an auxiliary winding arranged in parallel with the end turns of said electrical winding and forming therewith a condenser, and a safety device connected between said auxiliary winding and ground.

In witness whereof, I have hereunto set my hand this 23 day of April, 1915.

ALBERT HUNDT.
